UNITED STATES PATENT OFFICE

162,967

BERRY BASKET OR THE LIKE

Harry G. Long, Los Angeles, and Mildred D. Youker, Lynwood, Calif.; said Youker assignor to said Long

Application March 20, 1950, Serial No. 8,656

Term of patent 14 years

(Cl. D58—12.7)

To all whom it may concern:

Be it known that we, Harry G. Long and Mildred D. Youker, citizens of the United States of America, residing in the city of Los Angeles and the city of Lynwood, respectively, in the county of Los Angeles and State of California, have invented a new, original, and ornamental Design for a Berry Basket or the like, of which the following is a specification, reference being had to the accompanying drawing, forming a part thereof.

We claim:

The ornamental design for a berry basket or the like, substantially as shown.

HARRY G. LONG.

MILDRED D. YOUKER.
